UNITED STATES PATENT OFFICE.

JOHN B. MORRIS AND GEORGE MCG. MORRIS, OF CINCINNATI, OHIO.

CANCELING-PUNCH.

SPECIFICATION forming part of Letters Patent No. 470,435, dated March 8, 1892.

Application filed July 27, 1891. Serial No. 400,858. (No model.)

To all whom it may concern:

Be it known that we, JOHN B. MORRIS and GEORGE MCG. MORRIS, citizens of the United States, residing at Cincinnati, Ohio, have invented new and useful Improvements in Canceling-Punches, of which the following is a specification.

Our invention relates to hand punching or canceling presses, its object being to produce a simple, compact, and powerful machine for use in banks and elsewhere for canceling checks or other documents, punching letters, receipts, &c., for stringing and making metal labels, and for similar uses.

15 To this end it consists in the lever-punching apparatus constructed as herein described, adapted, as shown, to the use of various punching-dies, seals, &c.

In the drawings herewith is exhibited an apparatus embodying our invention.

20 In the drawings, Figure 1 is a side elevation of the same complete; Fig. 2, a front elevation of the same; Figs. 3 and 4, details of punching and cutting dies used with the plunger as occasion requires.

25 Referring now more particularly to the drawings, A designates a base-plate, upon which is mounted a column B, terminated above by two overhanging jaws b' b' and extended midway at the side beneath the jaws by a guide projection b². The jaws b' are pierced transversely for the reception of a short pivot-shaft a, and the guide projection b² is bored vertically for the reception and play of a plunger C, which latter is provided at its lower end for the reception of interchangeable dies, cutters, seals, &c., and is pivotally connected above to an operating-eccentric, all as hereinafter more particularly de-

30 scribed.

The shaft a is journaled in and through the jaws b', carrying an eccentric D between the jaws and an operating-handle E upon the projecting end at one side, both being rigidly connected to the shaft. The eccentric is provided with a detachable yoke and strap d, seating below in a slotted recess at the upper end of the plunger C, with pressure-surfaces in constant contact and held by a pin c. The 35 lower end of the plunger is recessed vertically and provided with a set-screw e for the

reception and holding of interchangeable dies or punches, which are provided with projecting shanks adapted to engage in the recess of the plunger and be retained by the set-screw. 55

In the main figures of the drawings the apparatus is shown provided with a check-canceling cutter consisting of a block F, having an engaging shank, as above described, and four cutting-knives f, placed back to back in the form of a cross, as shown in the section, Fig. 4, taken on the line x of Fig. 2, and retained in the head F by set-screws, permitting their removal for resharpening, &c. In Fig. 3 the head F is shown provided with two "eyelet-punches" as commonly used in "stringing" letters, receipts, checks, &c., the construction otherwise being the same as that of the cutter first described.

For use with the cutter or double punch or similar devices intended to operate upon paper, cloth, leather, &c., in quantities, a plate G is provided, beneath which the mass of material is placed to be operated upon and which, by preventing the upward movement of the material when the cutter or punch is to be withdrawn, enables the latter to readily clear itself. The plate G is recessed at the front side to admit one of the cutting-knives to pass through it, and is secured to the column B or to the base-plate in any convenient manner, so as to be detached when it is not needed in use.

The base-plate A is recessed at a point beneath the plunger, so as to admit a block of lead or wood, as indicated by the dotted lines, to receive the impact of the cutting-edges or punches. A female die may be also placed therein when a male die is used with the plunger.

The upper part of the plunger A is screw-threaded, as shown, and provided with a follower-nut h, which serves as an adjustable stop to limit the downward movement of the plunger, as may be desired, so that the cutting-edges of the knives or punches may not be injured by unnecessary pressure.

90 The operation of the machine is sufficiently obvious.

We may vary the construction by forming the handle E as a part of or attached to the eccentric D, in which case the space between

the jaws $b' b'$ may be widened to admit the handle, and the shaft a might be a stationary pivot.

We claim as our invention and desire to secure by Letters Patent of the United States—

1. In a hand-press, the combination of the supporting-column provided with a guide-abutment, an operating-eccentric journaled above the same, an actuating-handle, a plunger reciprocating in and through said guide and having operating connection with the eccentric, and an adjustable stop carried upon said plunger and limiting its downward reciprocation by contact with the guide-abutment, substantially as set forth.

2. In a press of the character described, the combination of a detachable block terminating the plunger, provided with radial-plane sockets meeting at the center and extending outwardly through the block, plane rectangu-

lar cutting-blades adapted to fit and seat in said sockets and adjoin at the center, and set-screws threaded through the block and one side of each socket, respectively, to bear against the cutting-blade seated therein and hold the same by pressure against the opposite wall of the socket, substantially as set forth.

In testimony whereof we have hereunto set our hands in the presence of two subscribing witnesses.

JOHN B. MORRIS.
GEORGE McG. MORRIS.
